UNITED STATES PATENT OFFICE.

JAMES WARD, OF DELAVAL, ENGLAND, ASSIGNOR TO INTERNATIONAL OIL FURNACE COMPANY, LIMITED, OF SCOTSWOOD ROAD, DELAVAL, NEAR NEWCASTLE-ON-THE-TYNE, COUNTY OF NORTHUMBERLAND, ENGLAND.

PORTABLE FURNACE.

SPECIFICATION forming part of Letters Patent No. 695,015, dated March 11, 1902.

Application filed March 11, 1901. Serial No. 50,730. (No model.)

To all whom it may concern:

Be it known that I, JAMES WARD, a subject of the King of England, residing and having my post-office address at Scotswood road, Delaval, near Newcastle-upon-Tyne, county of Northumberland, England, have invented a certain new and useful Improvement in Portable Furnaces, of which the following is a specification.

10 This invention relates to an improved portable furnace for application to single or double flued boilers, gas-retorts, kilns for bricks, ware, and the like, drying-stoves, and for analogous purposes.

15 Referring to the accompanying drawings, Figure 1 is a front view of furnace; Fig. 2, cross-section thereof; Fig. 3, a longitudinal section; Fig. 4, an elevation of the back of the furnace, showing flues divided into two for 20 double-flued boilers, &c.; Fig. 5, cross-section of a fuel-tray.

The furnace consists of two chambers *a* and *b*, one behind the other, and the fuel used is crude petroleum, paraffin, or other suitable 25 oil; but oils more or less refined may be used. The fuel is vaporized and partially combusted in the front chamber *a*, and in the back chamber *b* the vapor or gas is heated and further 30 partial combustion takes place. The fuel is contained in one or more shallow troughs or trays *e*, one above the other, suitably supported either on a framing fixed to the furnace or on a framing *g*, that may be drawn out of the furnace, in the latter case said framing 35 being mounted on wheels *h*, adapted to run on rails or bars *j*. The trays preferably project a short distance outside the furnace, and the tops thereof are provided with sliding plates *f* or dampers to regulate the vaporization 40 of the oil. A suitably-supported pipe *k*, provided with a regulating valve or cock *l*, conveys the oil to the trays by means of short bent pipes *n*, having funnels on their ends, the supply to each tray being also provided with 45 a separate valve or cock *m*. Provision is made on said pipe *k* for connecting, by means of a flexible or other pipe, to the reservoir or tank containing the oil. The side walls of the furnace are hollow. A slide or door *o* in the 50 front of the furnace and at each side of the chamber and near the bottom admits air into

the hollow walls, said air being heated by passing backward and forward through a series of passages *p q r s t* until it is discharged through a flue *u* in the back and near the top 55 of the furnace. These passages may be checkered to give more heating-surface. The gas or vaporized oil is conveyed from the vaporizing-chamber *a* by a flue *c* in the bottom to the heating-chamber *b*, and out of this chamber by a flue *v* in the back of the furnace and immediately below the air-discharge flue. The dotted arrows show the direction or flow 60 of the heated air and the full arrows the flow of gas. The chambers are lined with any suitable refractory material. A suitable metallic casing *x* is provided for holding the whole together, and the furnace is carried on suitable wheels or rollers *w*.

When the furnace is used, the back of it is 70 closely connected to the front of the boiler, &c., so that the air and gas flues are in immediate and direct communication with the boiler-flue, &c., in which the air and gas combine and complete combustion takes place. 75 The mode of connection between the furnace and the boiler, &c., is modified to suit the individual case.

What I claim is—

In a furnace of the character described the 80 combination of a vaporizing-chamber *a*, a heating-chamber *b* in communication therewith at its lower part, tortuous air-passages on each side of said chambers *a b*, a slide for admitting air to the lowermost end of each of 85 said passages, an outlet *v* for discharge of gas from said heating-chamber *b*, a flue *u* for discharge of air from the uppermost end of each of said passages, trays *e* in said vaporizing-chamber for receiving the fuel, said trays being 90 mounted in a frame *g*, a supply-pipe *k* having a stop-valve *l* and cocks in said pipe *k* for regulating the flow to each tray through short pipes, provided with funnels, and a metallic casing *x* for holding the whole together, 95 substantially as described.

In witness whereof I have signed this specification in the presence of two witnesses.

JAMES WARD.
